UNITED STATES PATENT OFFICE

2,543,678

METHOD OF PRODUCING RECTIFIER ELEMENTS

Gerald Tumulo, Bryn Mawr, N. Y., assignor to
Radio Receptor Co. Inc., New York, N. Y., a
corporation of New York

Application October 13, 1948, Serial No. 54,231

5 Claims. (Cl. 175—366)

1

This invention relates to an improved method and apparatus for efficiently and rapidly producing rectifier elements in multiple.

Broadly, it is an object of this invention to provide a method and apparatus for producing rectifier elements in multiple from a base plate which is later subdivided; wherein a series of coatings or layers developing the rectifier effect are superimposed over an enlarged base plate on which there is adhesively mounted a series of insulating discs, which later serve as masking elements during the layer application and as insulating elements in the end product.

Specifically, it is an object of this invention to provide a method of and apparatus for producing rectifier elements in multiple from a base plate which comprises successively adhesively mounting a plurality of insulating discs in spaced relationship on the surface of a base plate successively coating the same with continuous layers of semi-conductive material and barrier liquid and discontinuous or spaced areas of counter-electrode material, the respective margins between the layers of counter-electrode material serving as the severing zone defining the individual rectifier elements being formed.

It is accordingly the object of this invention to provide a new method and apparatus for manufacturing rectifiers, and especially adapted to mass production.

This, and other objects, advantages and novel features of the invention will be apparent from the following description and the accompanying drawings.

In the drawings:

Fig. 1 is a front elevation of apparatus embodying the invention.

Fig. 2 is a horizontal sectional view on the line 2—2 of Fig. 1.

Fig. 3 is a vertical sectional view on the line 3—3 of Fig. 2.

Fig. 4 is a partial end elevation view on the line 4—4 of Fig. 1.

Fig. 5 is a plan view of a slide forming part of the apparatus of Fig. 1.

Fig. 6 is a vertical sectional view on the line 6—6 of Fig. 5.

Fig. 7 is a vertical sectional view on the line 1—1 of Fig. 6.

Figs. 8 through 12 are partial vertical sectional views illustrating successive steps of the methods.

Fig. 13 is a plan view of a base plate after processing in the apparatus of Fig. 1.

Fig. 14 is a transverse sectional view on the line 14—14 of Fig. 13.

2

Fig. 15 is a transverse sectional view showing a further process step.

Fig. 16 is a plan view illustrating a further step in the process.

Fig. 17 is a plan view of a completed assembly of rectifiers.

Fig. 18 is a plan view of a completed rectifier section.

Fig. 19 is a transverse sectional view on the line 19—19 of Fig. 18.

Referring to Figs. 1 through 7, the apparatus for adhesively mounting in multiple on the base plate masks which serve as insulating discs, includes a frame 20 having an upper horizontal shelf 21 supported on legs 22. A relatively heavy, substantially square base plate 23 is mounted on shelf 21, and secured to plate 23 are a pair of horizontally spaced, inverted L-shaped parallel rails 25 which extend beyond plate 23. Strips 24 secured to the extended portions of rails 25 act as extensions of the bearing surface 23. Bolts 26 act as outer stops for rails 25, and a third inverted L-shaped member 27 extends across the inner ends of the rails and has, near one end, a bore 28 for a purpose to be described.

A slide 30 is provided, and includes a plate 31, engaging plate 23 and strips 24, and an upper plate 32 secured to plate 31 and fitting between rails 25. Plate 31 has a reduced extension 33 carrying an operating handle 34 for reciprocating slide 30 between a loading position at the outer ends of rails 25 and an operating position at the inner ends of the rails. At its inner end, plate 31 carries a finger 36 projectable through bar 28 to engage the operator 37 of a microswitch 35 mounted on plate 23. Switch 35 is connected by conductors 38 to an electronic timer (not shown) which controls the operation of the mechanism.

The upper surface of plate 32 has four angle straps 41, one at each corner, which serve as location fixers for the metal plate 40 on which the rectifiers are formed. In the example shown, twenty-five individual rectifiers are to be formed on plate 40 in five rows of five sections each.

A relatively thick, substantially square block 42 rests on rails 25 and has twenty-five vertical bores 43 each having a bearing bushing 44 therein. Each bore is centered with respect to a rectifier section of plate 40. Resting on the upper surface of block 42 is a plate 46, with its lower surface recessed to form a slit 47 opening transversely of the direction of movement of slide 30. Plate 46 has twenty-five apertures 48 each aligned with a bore 43.

Slit or passage 47 extends beyond the outer rows of apertures 48, and is arranged to receive a sheet 50 of masking material, preferably paper, from a roll 51 mounted on a shaft 52 supported in bearings 53. Bearings 53 are mounted on the horizontal leg of an L-shaped bracket 54 secured on the side of frame 20. A support roller 56 may be mounted in bearings 57 between roll 51 and slit 47.

Paper insulating discs 60, which also serve as masks in the piercing step later described, are punched from adhesive coated insulation sheet 50 by means of punches 58 on a vertically reciprocable ram 55 having guides 61 slidable through apertures in plate or block 23. Each finger 58 is slidably engageable in apertures 48 and bores 43. Ram 55 is reciprocated by electrically operable or controlled mechanism connected to the timer controlled by switch 35.

The operation of the apparatus will now be described. Slide 30 is pulled to the left (Fig. 2) and a metal sheet 40 is located thereon by angles 41. Sheet 50, which is coated with an adhesive on its under surface, is pulled from roll 51 and fed through slit or passage 47 (Fig. 9). Slide 30 is then pushed to the right (Fig. 3), whereupon pin or plunger 36 passes through bore 28 and engages operator 37 to activate switch 35. This starts the electronic timer, which controls the reciprocating mechanism for ram 55.

Ram 55 moves down (Fig. 10) and punches 58 punch discs or masks 60 from strip 50, carrying them down through bushings 44 against plate 40. The timer maintains the ram in the down position, with punches 58 forcing discs 60 against plate 40, for a time sufficient to assure firm adherence of the discs against the plate. The ram then ascends to the position of Figs. 8 and 9 and the perforated strip 50 is withdrawn. Slide 30 is moved to the left to the loading position and plate 40, with twenty-five discs or masks 60 adhered thereto (Figs. 13 and 14) is removed.

The masked plate is next sprinkled with a rectifying material 61 such as selenium, covering both the surface of the plate and the discs or masks 60 (Fig. 15). The selenium or the like is then pressed firmly into adherence with the plate surface and the discs or masks 60, forming a continuous coating, after which the assembly is annealed in the usual manner.

Barrier layer liquid is then applied to the annealed selenium surface to form a continuous coating. Thereafter a grid 65 having a series of cross bars bounding openings 66, defining the location and area of the counter-electrode layer for the respective individual rectifier elements, is placed on the treated surface of the plate and counter-electrode material applied to each surface within the zones of the openings of the grid, thereby forming a series of spaced layers of counter-electrode material which are greater in area than the discs aforesaid.

The grid 65 is then removed and the coated base plate may be fed through a shear which cuts the same into strips along and centrally of the parallel margins 67 from which counter-electrode material has been masked by the cross bars bounding the openings 66 as aforesaid, or the base plate may be fed through a combined punch and shear which severs the individual rectifiers 70 along the center line of the cross bar masked margins 67 and simultaneously punches apertures 68 through masking discs 60 and plate 40. The punching operation leaves an annular insulation disc 69 around the aperture, between the coatings

and the base, and prevents contact of rough edges of such coatings, particularly the counter-electrode material, with the base plate at the aperture; since the counter-electrode in no event extends up to the severing line, no problem of short-circuiting can exist at the external peripheral edges of the severed individual rectifier elements. The completed rectifiers may then be electroformed, and assembled on a rod in the usual manner.

The described method and apparatus provide a rectifier in which the semi-conductor and counter-electrode are in contact throughout their areas, but separated from the base at the zone 15 of the insulator disc.

While a specific embodiment of the invention has been shown and described in detail to illustrate the application of the principles thereof, it will be understood that such embodiment is exemplary only and that the invention may be otherwise embodied without departing from such principles.

I claim:

1. A method of manufacturing a plurality of 25 selenium or the like rectifiers each of which incorporates as a base a section from a metal plate which is later sub-divided, comprising applying discs of insulating material to the surface of the plate in the zone of the center of each section, applying to such one surface a continuous coating of semi-conductive material, applying a continuous barrier layer to the coating, applying a counter-electrode material over the barrier layer in laterally spaced layers, each of which is superimposed over and is greater in area than the insulating disc, severing the thus treated plate in the spaces between the counter-electrode layers to form individual rectifier sections, and piercing the individual sections at their centers to 30 provide an insulating ring on the base, bounding a formed aperture.

2. A method of manufacturing a plurality of 45 selenium or the like rectifiers each of which incorporates as a base a section from a metal plate which is later subdivided, comprising adhesively applying discs of insulating material to the surface of the plate in the zone of the center of each section, applying to such one surface a continuous coating of semi-conductive material, applying a continuous barrier layer to the coating, applying a counter-electrode material over the barrier layer in laterally spaced layers, each of which is superimposed over and is greater in area than the adhering insulating disc, severing the thus treated plate in the spaces between the counter-electrode layers to form individual rectifier sections, and piercing the individual sections at their centers to provide an insulating ring on the base, bounding a formed aperture.

3. A method of manufacturing a plurality of 60 selenium or the like rectifiers each of which incorporates as a base a section from a metal plate which is later subdivided, comprising adhesively applying discs of insulating material to the surface of the plate in the zone of the center of each section, applying to such one surface a continuous coating of semi-conductive material, applying a continuous barrier layer to the coating, applying a counter-electrode material over the barrier layer in laterally spaced layers, each of which is superimposed over and is greater in area than the adhering insulating disc, severing the thus treated plate in the spaces between the counter-electrode layers to form individual rectifier sections, and simultaneously with such severing 65

piercing the individual sections at their centers to provide an insulating ring on the base, bounding the formed aperture.

4. A method of manufacturing a plurality of selenium or the like rectifiers each of which incorporates as a base a section from a metal plate which is later subdivided, comprising applying discs of insulating material to the surface of the plate in the zone of the center of each section, applying to such one surface a continuous coating of semi-conductive material, applying a continuous barrier layer to the coating, mounting on the barrier layer a masking grid having openings delineating the areas of the counter-electrode for the individual sections, applying a coating of counter-electrode material over the barrier layer within the grid openings, removing the grid, severing the individual rectifier sections along the zones masked by the grid, and piercing the sections at their centers to provide an insulating ring on the base around the formed aperture. 15

5. A method of manufacturing a plurality of selenium or the like rectifiers each of which incorporates as a base a section from a metal plate which is later subdivided, comprising applying discs of insulating material to the surface of the 20

plate in the zone of the center of each section, applying to such one surface a continuous coating of semi-conductive material, applying a continuous barrier layer to the coating, mounting on the barrier layer a masking grid having openings delineating the areas of the counter-electrode for the individual sections, applying a coating of counter-electrode material over the barrier layer within the grid openings, removing the grid, severing the individual rectifier sections along the zones masked by the grid, and simultaneously with such severing piercing the sections at their centers to provide an insulating ring on the base around the formed aperture.
